UNITED STATES PATENT OFFICE.

BERNARDO MORETTO, OF WESTVILLE, ILLINOIS.

DESIGN FOR A CHEST OF DRAWERS.

Application filed September 27, 1928. Serial No. 28,291. Term of patent 7 years.

To all whom it may concern:

Be it known that I, BERNARDO MORETTO, a citizen of the United States, residing at Westville, in the county of Vermilion and State of Illinois, have invented a new, original, and ornamental Design for a Chest of Drawers, of which the following is a specification, reference being had to the accompanying drawing, forming part thereof.

The figure is a perspective view of a chest of drawers, showing my new design.

I claim:

The ornamental design for a chest of drawers, as shown.

BERNARDO MORETTO.
